OIL FILTER

Harry A. Dever, Exeter, Nebr.

Application March 18, 1941. Serial No. 384,012

3 Claims. (Cl. 210—165)

This invention relates to oil filters of the character commonly applied to automobiles in connection with an oil pump for sending lubricating oil to the various parts of the machine.

The object of this invention is the construction of an oil filter having parts of special construction and particular arrangement whereby it is believed a superior filtering means is attained which is especially easy to take apart and to be thoroughly cleaned with but a minimum of labor. *Patent Visevol.*

The accompanying drawing illustrates the construction of this filter, and Fig. 1 represents a top plan view, and Fig. 2 is a fragmentary sectional view of the top taken on the inclined line 2—2 of Fig. 1 and intended to illustrate the by-pass uptake and the valve therein. Fig. 3 is a vertical sectional view showing all the parts assembled, and Fig. 4 is a vertical elevational view showing the glass plate in a suitable top extension and means for securing the plate in the top.

Throughout the description and drawing the same number is employed to refer to the same part.

Considering the drawing, a cupped top body portion 1 has on one side two projecting pierced ears 2 and 3 by means of which the whole may be attached to a suitable support.

As best shown in Fig. 3, the top 1 has an extended open portion 4 provided with a seat for a plate, and by means of a ring nut 5 a circular glass plate 6 is held in the seat and permits the inspection of the interior of the top from outside. The form of the open extension of the top and the glass plate and its holding elements may be varied within the scope of this application.

In Fig. 3 will be noted an outlet 7 for oil passing out of the top 1 by way of the outlet tube 8 shown in Fig. 4. If desired the outlet 9 may be closed by the screw plug 10. Outlet 9 has the same opening into the top as is provided for the fellow outlet 8.

What is termed for the purposes of this explanation a bowl 11 is located below the top 1, and in connection therewith as illustrated. The top and bowl are secured in contact by means of a cap nut 12 on the threaded end of an axial bolt rod 13. The rod has a lower end head 14 shouldered to meet a sleeve enlargement 15 at the bottom of the bowl. It will be noted that the upper edge 16 of the bowl is made somewhat

thicker to contact with the top, and this contact may be changed into a different formation.

As shown in Fig. 3 the bolt rod has a shoulder 17 at its upper portion and engaging this shoulder in Fig. 3 is the central sleeve portion 18 of an inner portion termed for this explanation a core. The sleeve fits the bolt rod lengthwise. The top of the core 19 is in the form of a circular disk, the upper surface of the disk being 10 provided with concentric grooves 20, the bottom of each groove having a perforation 21 as shown in Fig. 2. In Fig. 3 will also be noted the passage or chamber 22 in the top of the core. This passage is formed in a downwardly extending 15 circumferential edge portion of the core marked 23. The upper part of the core fits into the top 1 as shown and the downwardly extended part 23 has an encircling groove 24 constructed with a passage 25 leading into the bowl 11. The passage 24 is arranged in communication with the 20 oil inlets 26 and 27 shown in Fig. 4, either of which may be used as desired, the other being closed.

As best shown in Fig. 3, the core sleeve 18 is surrounded by a cylindrical filtering member 28 which has a closed bottom 29 attached by means of the ring nut 30 to the lower end of the core sleeve.

In Figs. 2 and 3 will be noted the upper disk 31 provided with spaced perforations 32 and made of any chosen material. Top disk 31 is centrally pressed down by the thumb nut 33 on the threaded end of the bolt rod 13 and the pressure exerted on the disk top 20 of the core as illustrated. The top 1 and the core are thus clamped together.

Considering Fig. 2 there will be noted an uptake passage 34 leading to a vertical bore 35 normally closed by the ball valve 36 controlled by coil spring 37 which is kept by means of nut 38 in the vertical cavity 39 above the valve.

In the operation of this invention, the bowl may be drained by removing screw plug 40 in the bottom of the bowl. It will be particularly observed that by removing the bolt rod all the parts of this filter may be detached one from another and each given a thorough cleaning when necessary. The oil enters the bowl by way of the encircling outside groove in the core and passes into the filtering member. Through the open upper end of the member oil enters the side passage in the top of the core continuing through the perforations of the disk of the core and the cover disk thereon into the top of the body top and out through one of the oil outlets. If the

filtering member clogs for any reason, the oil pressure in the valved uptake lifts and the oil is discharged into the body top thus relieving any over pressure.

Having described my invention, I claim:

1. An oil filter comprising a top portion provided with devices for engaging a support, a bowl portion arranged below the top, an axial bolt rod extending through the said top and bowl and having a threaded upper end, a cap nut engaging the threads of the rod above the top and adapted to secure the top and bowl together in detachable relation, a core portion having a central sleeve body constructed to fit on said bolt rod lengthwise, devices constructed to secure the core on the rod, said core having an annular disk upper portion, said disk having grooves in its upper surface and perforations in the grooves, the said disk being extended downwardly around its edge and said downward portion having an outside encircling groove, oil inlets in communication with the said outside groove, said groove being constructed with openings whereby oil enters the bowl, a cylindrical filter carried by the said core sleeve and engaging the said downwardly extended edge portion of the disk, said disk having an oil cavity arranged to receive oil from within the filter and whereby filtered oil may pass through the disk perforations into the disk grooves, and said top being constructed with oil outlets.

2. In an oil filter, a top portion provided with devices for engaging a support, a bowl portion arranged below the top, an axial bolt rod extending through the said top and bowl and having a threaded upper end, a cap nut engaging the threads of the rod above the top and adapted to secure the top and bowl together in detachable relation, a core portion having a central sleeve body constructed to fit on said bolt rod lengthwise, devices constructed to secure the core on the rod, said core having an annular disk upper portion, said disk having grooves in its upper

- surface and perforations in the grooves, the said disk being extended downwardly around its edge and said downward portion having an outside encircling groove, oil inlets in communication with the said outside groove, said groove being constructed with openings whereby oil enters the bowl, a cylindrical filter carried by the said core sleeve and engaging the said downwardly extended edge portion of the disk, said disk having an oil cavity arranged to receive oil from within the filter and whereby filtered oil may pass through the disk perforations into the disk grooves, said top being constructed with oil outlets, and said top having a by-pass extending from the said outside encircling disk groove into said top and having a pressure operated spring governed valve arranged to open and close the by-pass.
3. An oil filter, comprising a top body portion, a bowl portion, means for securing the top portion and the bowl portion together in detachable relation comprising an axial bolt rod, a core portion carried by the rod and having an upper perforated disk portion located in the top, a filtering member having a closed bottom attached to said core, the filtering member being open at the upper end, the said core having an annular downwardly extending portion at the edge thereof constructed to fit closely around the open end of the filtering member, said top body portion and said downwardly extending portion of the core having communicating passages whereby oil from the exterior may flow into the bowl and into the filtering member, the said top body portion having oil inlet connections and oil outlet connections constructed and arranged to be coupled to oil tubes, and the said body portion having an extended open portion, a glass plate arranged in the said open extension of the top and means for securing the plate removably in the said open extension.

HARRY A. DEVER.
